UNITED STATES PATENT OFFICE.

LEE G. DANIELS, OF ROCKFORD, ILLINOIS.

AUTOMATIC MULTIPLE-SPINDLE METAL-WORKING MACHINE.

Application filed September 27, 1920. Serial No. 412,946.

To all whom it may concern:

Be it known that I, LEE G. DANIELS, a citizen of the United States, residing at Rockford, in the county of Winnebago and State of Illinois, have invented certain new and useful Improvements in Automatic Multiple-Spindle Metal-Working Machines, of which the following is a specification.

This invention pertains to automatic metal working machines, and has more particular reference to the general type disclosed in my Patent No. 1,274,859, dated August 6, 1918. Such class of machines is characterized by the inclusion of a plurality of tool carriers and work carriers, which are relatively indexed in step by step movements to bring the work successively into operative relation with the various tools; and at each station a relative movement between the tools and work is effected, preferably by feed of the tools, to simultaneously perform a plurality of operations. Such machines are further characterized by the provision of mechanism which automatically regulates and controls the various movements in a predetermined manner.

The primary object of the present invention is to provide an automatic multiple spindle metal working machine of the character described, of novel construction, designed to obtain a most efficient means for machining parts in large quantities, with the use of semi-skilled labor to operate the machine after it is set up and timed for the various operations, thus offsetting increasing labor costs and effectually meeting the need for increased production.

Another important object is to generally improve and simplify a machine of the general type disclosed in my patent mentioned above.

Still another object is to provide an automatic metal working machine of the character in mind, designed along such simple and practical lines as to satisfactorily and effectually meet the various conditions and requirements of a commercial product.

In furtherance of these general objects, I have embodied in the present machine, certain principles disclosed and claimed in my patent mentioned above, these being embodied in a generally improved and simplified construction, in combination with other novel features and departures, the principles and construction of which will be described hereinafter.

Referring to the drawing;

Figure 1 is a side elevation of an automatic metal working machine embodying my improvements;

Fig. 2, a fragmentary view partly in section, of the lower portion of the machine and certain control mechanism therein, in the position shown in Fig. 1;

Fig. 3, a plan sectional view taken substantially on the line 3—3 of Fig. 2;

Fig. 4, a vertical sectional view taken substantially on the line 4—4 of Fig. 3;

Figs. 5 and 6, fragmentary sectional views of a part of the control mechanism shown in Fig. 2, in neutral and rapid approach positions, respectively;

Fig. 7, a detail section taken on the line 7—7 of Fig. 2;

Fig. 8, a detail section taken on the line 8—8 of Fig. 4;

Fig. 9, a fragmentary view, looking at the inner side of the cam bar 96, mentioned hereinafter, showing an operative relation of the cam 101 and cam followers;

Figs. 10 and 11, plan and side views respectively, of the parts shown in Fig. 9;

Fig. 12, is a detail section taken on the line 12—12 of Fig. 4;

Fig. 13, a rear view of lever 92 described hereinafter.

Fig. 14, a horizontal section taken substantially on the line 14—14 of Fig. 1; and

Fig. 15, a top view of the gearing for driving the tool spindles.

It should be understood that the frame or housing of the machine might be of any suitable or preferred construction. In the present instance, it consists of a cylindrical table-supporting portion designated generally by the character 15, a control mechanism housing divided into compartments 16 and 17, and an upright standard 18 carrying an overhead spindle gearing housing, designated generally by character 19.

A work table 21, supported on the bearing 22 on the housing portion 15 is revoluble thereupon and about the central vertical cylindrical column 23. This column 23 is rigidly secured to and supported at its lower end upon the central portion 24, integral with the housing 15, and is held in position at its upper end by the housing 19. The work table is adapted to carry a plurality of circumferentially spaced work holders in whatsoever form as may be required for the particular work at hand. These work

holders may be either jigs, fixtures or chucks, and in the present instance, the table is constructed to carry six equally spaced work holders. By means of mechanism described hereinafter, the work table will be rotated in step by step movements to carry the work successively to the different stations at which to be operated upon by the respective tools and to be finally carried to an unloading station at which a new piece of work is substituted for the finished piece.

The tools are supported by a carriage designated generally by character 25 which slides vertically on the central column 23 for the purpose of bringing the tools into and out of operative relation to the work on the table. The tool carriage is moved vertically by a lead screw 43 engaging a nut 44, which has diametrically opposed arms 114 extending through slotways 115 in the column 23 and securely bolted to the tool carriage beyond the periphery of the column. The tool carriage has a laterally extending arm 26 slidably engaging the vertical ways 27 on the upright column 18, as shown in Fig. 14, for steadyng and holding the tools in proper alignment. The tools, not shown, are preferably carried by spindles 28 circumferentially spaced about and mounted for rotation on the carriage 25, as is well known in this art.

The spindles are driven at the desired speeds by gearing contained within the housing 19. This gearing may be driven by an independent motor or from the same motor which drives the table indexing and tool feeding mechanism which will be described later. In the present instance, I have employed but a single motor for driving all of the mechanisms. The motor 29 drives the power shaft 31 (Fig. 4) through the agency of a link chain (not shown) connecting with the gear 32 on said shaft. This shaft 31 drives a vertical shaft 33 through means of spur gears 34 and bevel gears 35, and the vertical shaft 33 drives a horizontal shaft 36 within the housing 19. A vertical shaft 116 journaled in said housing co-axial with the central column 23 is continuously driven from the shaft 36 by bevel gears 117, one of which is integral with a spur gear 37 on the shaft 116. This central gear 37 is in permanent driving connection with all of the tool spindles 28 through means of intermediate shafts 38, 38' and 38'', and gearing between these intermediate shafts and the respective spindles. As shown in Fig. 4, the intermediate shaft 38 has a gear 39 meshing with the central gear 37 and a gear 41 of small diameter meshing with a gear 42 of larger diameter on the spindle, thus driving this spindle at a relatively slow speed. As shown in Fig. 15, the intermediate shaft 38' has a gear 39' of the same diameter as

the gear 39 meshing with the central gear 37 and is further equipped with a pair of gears 41' and 41'' meshing respectively with gears 42' and 42'' on the adjacent spindles. It follows that the single intermediate shaft 38' drives two spindles at different speeds, by reason of the cluster arrangement of gears of different diameters. The series of intermeshing gears 41—42, 41'—42', and 41''—42'' are "change gears" in the sense that they are quickly removable by removal of the retaining nuts 40, Fig. 4, for the substitution of other sets of gears of different ratios. This provides a quick, practical and inexpensive means whereby the speed of the respective spindles may be changed. The gearing between the intermediate shaft 38'' and the adjacent pair of spindles may be the same as that just described with respect to the intermediate shaft 38'. The tool spindles 28 are splined in connection with their respective driving gears so that the spindles may be moved vertically by the tool carriage 25 as is well known in this art.

The lower end of the carrier lead screw 43, suitably journaled in the housing or base, is equipped with a fixed worm gear 45 and has suitable thrust bearings to take the end thrust resulting from moving the tool carrier vertically. A worm 46 fixed to the feed shaft 47 (Fig. 2) drives the worm gear 45, and by revolving the shaft 47 in opposite directions the tool carrier 25 will be fed toward and from the work table, as will be obvious. Automatic control mechanism which will be described presently is provided for driving the shaft 47 to move the tool carrier through what I term rapid approach toward the work, feed and quick reverse movements.

The mechanism for indexing the work carrier will now be described, reference being had to Figs. 3, 4 and 12. It is desired to positively lock the work table and hold it against vibration during the period that the work is being operated on by the tools. After the tools have been withdrawn, it is desired to index the table in an accelerating movement and then to gradually check its momentum until the table is brought to a stop, thereby performing the indexing movement in a most efficient manner and without danger of imposing undue strain on the parts. To this end, the table is equipped with a bevel gear 48 which meshes with a bevel pinion 49 fixed to a shaft 51 journaled in suitable bearings in the housing and equipped with an eccentrically located block 52 disposed in a slot or guide-way 53 diametrically disposed on a rotatable member 54. It will be observed that the shaft 51 and the member 54 are eccentric, so that when the member 54 is revolved the block 52 will move outwardly in the

slot 53 in an accelerating movement during one half revolution, and during the remaining half-revolution, the movement of the block and its shaft 51 will be gradually diminished, it being assumed, of course, that the member 54 revolves at a substantially uniform speed and makes only a single revolution. By means of this construction, the work table 21 will be started slowly in 10 its indexing movement, which will be gradually accelerated and then gradually diminished until brought to a stop. Rotation of the member 54 is controlled in part from the work table by means of a locking bar, 15 designated generally by character 55, Fig. 3, and through the agency of a friction clutch on the shaft 56. The locking bar 55, radially disposed with respect to the work table and slideable lengthwise in suitable bearings, 20 is constantly urged inwardly by a spring 57 to engage its tapered end 58 in a correspondingly tapered socket 59 in the work table. The locking bar is adapted to actuate through means of a lever 61, the shiftable 25 driving element 62 of said clutch to connect the driven member 63 to the shaft 56, and thereby revolve the member 54 through the chain 64. The connection between the lever 61 and the shiftable clutch element 62 is best 30 shown in Fig. 8. A pair of yoked members 60 and 70 integrally connected and pivotally mounted as shown, are connected respectively to the lever 61 and the clutch yoke. This construction allows lateral movement of the 35 lever 61 due to the locking bar 55 and shaft 56 being non-parallel. The shaft 56 is driven from the power shaft 31 through two sets of reducing gears 65 and 66. It will be manifest that the locking bar effectually 40 secures and holds the work table against rotation and that upon withdrawing said locking bar by means of a slide cam which will be described hereinafter, the lever 61 will be actuated to engage the clutch member 62— 45 63, thereby causing the member 54 to be revolved and the table to be indexed. Just after the table commences its indexing movement the tapered end 58 of the locking bar will be urged by the spring 57 against the 50 periphery of the work table so as to be free to enter the next succeeding tapered socket therein. There is one socket 59 for and corresponding in position to each work holder, and when the table has been indexed one station, the locking pin will enter the tapered 55 socket thereat, thereby disengaging said clutch and stopping rotation of the indexing mechanism. Under certain conditions it is desired to index the table more 60 than one station at a time, and in such event I provide plugs 67 for insertion into any of the sockets or openings 59, so as to preclude entrance of the locking pin therein, and thus cause the table to be indexed another position 65 or until an open socket 59 is presented to the locking bar. In the present instance, each alternate socket 59 is closed by a plug 67, so that the work in its cycle will stop at only three stations instead of six as would be the case if these plugs were removed. 70

The tool carrier feed mechanism and the automatic control therefor, will now be described. In the present machine I employ as in my patent mentioned above, separate controllable devices for driving a feed shaft 75 to produce the rapid approach, feed and reverse movements, this being done preferably through means of separate friction clutches. Referring now especially to Fig. 2, these 80 clutches are designated generally by character 68 for the rapid approach, 69 for the feed, and 71 for the reverse. Instead of arranging all of the clutches on a single shaft as in my former patent, I mount the rapid approach and reverse clutches on a secondary shaft 72 and the feed clutch on the feed shaft 47. These clutches are preferably of a friction type, adapted to be engaged respectively by expander arms. The 85 driving element of the feed clutch is in the form of a spur gear driven from a spur pinion 73, Fig. 4, in turn driven by change speed gears 74 from the shaft 56. By shifting the expander 75, the expander arm 76 will be actuated to frictionally engage the 90 clutch 69, so as to drive the shaft 47 in a feed movement. A lever 77 is employed to shift the expander 75. The clutches 68 and 71 each include an element in the form of a spur gear in driving connection with the feed shaft 47, the connection between the clutch 68 and the shaft being direct and that between the clutch 71 and the shaft being through the intermediary of a reversing gear 78, as shown in Fig. 7. The shaft 100 95 105 110 115 120 125 130 72 is continuously revolved by means of a spur pinion 79, which meshes with the larger spur gear of the set 66, Fig. 4. A single expander member 81, splined on the shaft 72, is adapted to be shifted in opposite directions by means of the lever 82 for engaging either the clutch 68 or 71. When shifted to the right as shown in Fig. 2, the expander arm 83 will be actuated to engage the reverse clutch, and when shifted to the left as shown in Fig. 6, the expander arm 84 will be moved to engage the rapid approach clutch 68. It will be here noted that the part 85 on the expander member 81, which actuates the arm 84, is so shaped that upon continued movement of said member 81, to the left, the arm 84 will drop behind a shoulder on the part 85, thus disengaging the clutch 68 and permitting the member 81 to continue idly in its movement to the left. This is for the purpose of permitting both the clutch-actuated levers 77 and 82 to be operated from a common slide rod 86 and to permit the clutch 69 to be engaged subsequently to the clutch 68 upon moving said

slide rod 86 inwardly. The slide rod 86 constantly urged to the left, viewing Fig. 2, by an expansion spring 89, may be moved to the right either by a hand lever 91 at the front 5 of the machine or by a lever 92 connected to a control rod 93. The lever 92, a rear view of which is shown in Fig. 13, comprises upper and lower sections pivotally connected at 90 at an axis substantially at right 10 angles to the lever fulcrum 90'. It will be observed that a double-jointed connection is provided between the lever 92 and the rod 93 to allow for the necessary movement incidental to the non-parallel relation of the 15 rods 86 and 93; also that only a one-way connection is provided between the hand lever 91 and the slide rod 86, so that the latter rod is free to be operated independently of the hand lever. The control rod 20 93 slidably mounted in suitable bearings to move in a plane parallel with the locking bar, is equipped at its inner end with a roller 94 adapted to be actuated by one of the cam faces 95 fixed to the work table, 25 there being one such cam near each socket 59. A cam is removed in each instance that one of the tapered sockets 59 is closed by a plug 57.

In the position of the parts shown in Figs. 30 1 to 4 inclusive, the reverse clutch is engaged under the influence of the spring 89 so that the feed shaft 47 will be revolved in a direction to feed the tool carrier 25 upwardly to retract the tools. At a predetermined point in this reverse movement, the reverse clutch will be disengaged, throwing the feed mechanism into a neutral position and stopping the tool carrier. This is done by utilizing movement of the tool carrier 35 to throw out the reverse clutch just prior to stopping such carrier. The means through which the carrier movement is transmitted, consists of a vertical cam-carrying bar designated generally by character 96 secured to a lateral extension 97 of the work carrier arm 26. This bar 96 carries a plurality of relatively adjustable cams 98, 99 and 101, the two former being attached to the outer side of the bar as shown in Fig. 1, and the latter 40 to the inner side, as shown in Figs. 9 to 11 inclusive. These cams may be relatively adjusted in any suitable manner on the bar 96 for the purpose of actuating their respective mechanisms in whatever timed relation required to suit the particular conditions of the work at hand. With the tool carrier in its reverse movement and the bar 96 traveling upwardly, the first cam to function will be the cam 101, Fig. 9. This cam engages a 45 roller 102 on the locking bar 55 and withdraws such bar, causing the work table to be indexed in the manner described above. As soon as the inner end of the locking bar 50 engages the periphery of the table as was described above, the cam 98 on the bar 96

will engage the roller 103 on the control rod 93 and move this rod outwardly to a neutral position, that is, one in which the feed mechanism parts assume the position shown in Fig. 5, with the reverse clutch disengaged; thus bringing the work table to a stop. This movement to neutral position causes the slide rod 86 to be moved inwardly until the spring-pressed detent 104, Fig. 2, engages in the notch 105 in said rod, thereby holding the rod and its associated parts in such neutral position. In the meantime, the work table is being indexed, and just before the completion of the indexing movement the next succeeding cam 95 on the work 50 table will engage the roller 94 and move the control rod 93 outwardly sufficiently to engage the rapid approach clutch, in the manner shown in Fig. 6. This will cause the tool carrier to be fed down in a rapid traverse movement, the position of the shiftable parts of the feed mechanism being maintained by the detent 104 engaging in the next notch 106 in the slide rod 86. When the tools reach the desired proximity to the work 55 the cam 99 on the bar 96 will engage the roller 103 and again move the control rod 93 outwardly, thereby shifting the clutch levers 77 and 82, disengaging the rapid approach clutch 68 and engaging the feed 60 clutch 69. This position of the rod 86 is maintained by the detent 104 engaging in the outermost notch 107 in said rod. The feed depth may be suited to the requirements and in this machine may be anywhere from 1 to 8 inches, according to nature of the work. The feed will be instantly stopped at the desired point by a trip device, consisting of a trip rod 108 adjustably connected to and moving with the arm 97 of the tool carrier, which rod actuates a lever 109, which in return withdraws the detent 104, allowing the compressed spring 89 to instantly disengage the feed clutch and throw in the reverse clutch. In order that the feed 70 clutch shall be instantly disengaged, I provide a lost motion connection between the lever 77 and rod 86, consisting of a slot in said lever and a pin on the rod, whereby the rod in its movement under the influence of the spring 89 will require certain momentum and strike the shifter lever 77 with such impact as to stop the feed instantly.

Referring back to the point in the operation when the rapid approach clutch is engaged, causing the tool carrier and its connected parts to travel downwardly, it will be observed that the roller 102 on the locking bar will be disposed in the path of the cam 101; and in order to avoid interference of these parts, I have so constructed this cam that it may be shifted to one side and give way to the roller as the cam moves down past the roller. This operation is indicated in dotted lines in Fig. 9, it being 80

observed that the inclined cam plate 101 is pivoted at 111 and urged by a spring 112 to the operative position shown in full lines. The cam is thus free to swing out of the way of the roller so as to avoid interference, and will be returned to operative position after having passed the roller.

A hand trip device is provided permitting release of the detent 104 at will, and consists of a handle 113 suitably connected to the lever 109 so that by pulling said handle outwardly the lever 109 will be actuated similarly to actuation by the trip rod 108.

In practice, the machine will be set up to perform whatever operations are required for the particular work to be done. The spindles might be equipped with either boring, reaming, facing or turning tools, or for tapping with collapsible taps, or for drilling multiple offset holes by means of attaching a multiple spindle auxiliary head to any of the spindles. The table will be equipped with suitable work holders or fixtures and the various cams and control mechanisms set to secure the desired table-indexing movements and control of the tool carriage. Assuming the machine in operation in the position shown in Figs. 1 to 4 inclusive, the tool carriage has just started upwardly in its rapid reverse movement. This will continue until the carriage nears its highest elevation, whereupon the locking bar 55 will be withdrawn by the cam 101 on the cam bar 96, thereby causing the table to be indexed. It will thus be seen that the tool carriage in its reverse movement actuates mechanism for causing the work table to be indexed. Just after the table has commenced its indexing movement, and the locking bar 55 is riding on the periphery of the table, the cam 98 on the bar 96 will actuate the control rod 93, so as to disengage the reverse clutch and throw the feed mechanism into neutral, whereupon the tool carriage will stop. During this time, the work table is indexing, and just prior to the finish of its indexing movement, the next succeeding cam 95 will actuate the control rod 93, throwing in the rapid approach clutch and causing the tool carriage to be fed downwardly in a rapid traverse movement. It will thus be noted that the work table in its indexing movement actuates mechanism which puts the tool carriage into operation again. Shortly after the rapid approach is thrown in, the locking bar enters the next succeeding socket 59 in the work table, thereby disengaging the indexing clutch and locking the work table in a set position. When the tools in their downward movement reach the desired proximity to the work, the cam 99 on the bar 96 operates the control rod 93 to disengage the feed clutch and cause the tools to be slackened in their travel to the requisite feeding speed. Cut-

ting operations are now being simultaneously performed on a plurality of pieces of work and when the proper depth has been reached the trip rod 108 will release the feed mechanism, causing the feed to be instantly stopped and the reverse clutch to be engaged, thus completing a cycle of the machine.

It is believed that the foregoing conveys a clear understanding of the objects preferred above and of the principles and operation of my improvements, and while I have illustrated and described but a single working embodiment thereof, it should be understood that various changes might be made in the construction and arrangement without departing from the spirit and scope of the invention as expressed in the appended claims:

I claim:

1. In a multiple spindle machine of the character described having a work carrier and a multiple spindle tool carrier, mechanism for relatively moving said carriers in rapid approach, feed and reverse movements, mechanism for indexing one of the carriers, control mechanism for automatically causing the first mentioned mechanism to produce said rapid approach, feed and reverse movements in predetermined relation, and means operable at the will of an operator for causing the first mentioned mechanism, during control thereof by said control mechanism, to function different from the predetermined automatic operation.

2. In a multiple spindle machine of the character described having a work carrier and a tool carrier, mechanism for relatively moving said carriers in rapid approach, feed and reverse movements, mechanism for indexing one of the carriers, control mechanism including a cam bar moving with one of the carriers and having cams for putting said indexing mechanism into operation, for effecting said feed movement, and for stopping said reverse movement, and means operated by the indexing carrier for effecting said rapid approach movement.

3. In a multiple spindle machine of the character described having a work carrier and a tool carrier, mechanism for relatively moving said carriers in rapid approach, feed and reverse movements, mechanism for indexing one of the carriers, control mechanism including a cam bar moving with one of the carriers and having cams for putting said indexing mechanism into operation, for effecting said feed movement, and for stopping said reverse movement, and a trip mechanism operated by the cam-moving carrier for stopping the feed at a predetermined point.

4. In a multiple spindle machine of the character described having a work carrier and a tool carrier, mechanism for relatively

- 6 moving said carriers in rapid approach, feed and reverse movements, mechanism for indexing one of the carriers, control mechanism including a cam bar moving with one of the carriers and having cams for putting said indexing mechanism into operation, for effecting said feed movement, and for stopping said reverse movement, and means operable at the will of an operator for stopping the feed movement.
5. In a multiple spindle machine of the character described having a work carrier and a tool carrier, mechanism for relatively moving said carriers in rapid approach, feed and reverse movements, mechanism for indexing one of the carriers, control mechanism including a cam bar moving with one of the carriers and having cams for putting said indexing mechanism into operation, for effecting said feed movement, and for stopping said reverse movement, and a manually controllable means operable at the will of an operator for effecting any operation obtained by automatic operation of said control mechanism.
6. In a machine of the character described, the combination of a work carrier and a tool carrier, one of which is adapted to be indexed and the other moved toward and from the index-carrier, a locking bar having a tapered end adapted to enter a socket in the index-carrier, means operated by said other carrier in its movement relatively to the index-carrier for withdrawing said locking bar, and means operated by the locking bar in its withdrawing movement for indexing the index-carrier.
7. In a machine of the character described, the combination of a suitable frame, an upper right cylindrical column secured at its upper and lower ends respectively to the frame, a work carrier revolved about the column, a tool carrier slidably longitudinally upon the column toward and from the work carrier, a screw shaft co-axially within the column, an internally threaded member on the tool carrier engaging the screw shaft, and means for revolving the shaft for moving the tool carrier lengthwise on said column.
8. In a machine of the character described, a work carrier and a tool carrier, one of which is adapted to be moved toward and from the work, cam-carrying means traveling with said movable carrier, mechanism adapted to be actuated by a cam on said means for imparting movement to said carrier, said cam-carrying means being movable in opposite directions, and a shiftable cam carried by said means and operative only upon movement of said means in one direction.
9. In a machine of the character described, the combination with a work carrier and a tool carrier, one of which is adapted to be moved with respect to the other in rapid approach, feed and reverse movements, of mechanism for effecting such movements comprising a feed shaft, a clutch thereon for effecting the feed movement, a secondary shaft, a rapid approach and a reverse clutch on the secondary shaft adapted when engaged to respectively drive the feed shaft, and mechanism for engaging and disengaging said clutches in timed relation to effect said rapid approach, feed and reverse movements.
10. In a machine of the character described, the combination with a work carrier and a tool carrier, one of which is adapted to be moved with respect to the other in rapid approach, feed and reverse movements, of mechanism for effecting such movements comprising a clutch for each movement, a control member for engaging and disengaging the clutch, means for holding the control member in a set position with one of the clutches engaged, means actuated by movement of said carrier relatively to the other for releasing said control member from said set position, and means operable at the will of an operator for also releasing said control member from said set position.
11. In a machine of the character described, the combination with a work carrier and a tool carrier, one of which is adapted to be indexed and the other moved in rapid approach, feed and reverse movements, of mechanism for indexing the index carrier, mechanism operable on the other carrier for producing said rapid approach, feed and reverse movements, and cam-carrying means moving with the latter carrier for putting said indexing mechanism into operation while the other carrier is in its reverse movement, for stopping said movement and for subsequently effecting the feed movement.
12. In a machine of the character described, the combination of a central upright column, a work-carrier and a tool-carrier concentric with the column, one being revoluble thereabout and the other reciprocable thereon to bring the tools into and out of operative relation to the work, a lead screw within the column, and a nut engaging said screw, the column having diametrically opposed slots and the nut having opposed arms extending through said slots and fixed to the reciprocable carrier, stationary vertical ways at one side of the column, and a rigid arm extending laterally from the reciprocable carrier and slidably guided on said ways for steadyng and holding said carrier in alignment.
13. In a machine of the character described, the combination of a work carrier and a tool carrier, the latter equipped with a plurality of circumferentially spaced tool spindles, means for moving the tool carrier and spindles toward and from the work car-

rier, a continuously driven gear concentrically within the spindles, a plurality of intermediate shafts, and gearing between the central driving gear and said shafts and between the latter and the spindles, one of said intermediate shafts being disposed between two adjacent spindles and having gear connections therewith of different ratios.

14. A machine of the character described comprising a base, an upright standard rigid with respect to and reaching above the base at one side thereof, a column concentric with and fixed to the base and reaching above the same, a work table mounted to revolve upon the base and about said column, a multiple spindle tool carrier reciprocable upon the column above the table, and an overhead housing containing gearing for driving the spindles and supported wholly by said standard and column.

15. A machine of the character described comprising a base, an upright column rigid on the base, a work table revoluble about said column, a multiple spindle tool carrier reciprocable upon said column above the table, an upright housing rigid on the base and shaped to over-reach said column above the tool carrier, and gearing within and supported by said over-reaching portion of the housing for driving the tool spindles.

16. In a machine of the character described, the combination of a base, an upright column fixed to the base, a work table revoluble about said column, a multiple spindle tool carrier vertically slidable upon the column, an upright housing at one side of the work table rigid on the base and over-reaching and associated with said column above the tool carrier, and mechanism within and supported by said over-reaching housing for driving the tool spindles.

17. In a machine of the character described, the combination of a base, an upright column fixed to the base, a work table revoluble about said column, a multiple spindle tool carrier vertically slidable upon the column, an upright housing at one side of

the work table rigid on the base and over-reaching and associated with said column above the tool carrier, mechanism within and supported by said over-reaching housing for driving the tool spindles, and mechanism within the base for indexing the work carrier and reciprocating the tool carrier.

18. In a machine of the character described, the combination of a central upright column, a work-carrier and a tool-carrier concentric with the column, one being revoluble thereabout and the other reciprocable thereon to bring the tools into and out of operative relation to the work, a lead screw within the column, and a nut engaging said screw, the column having diametrically opposed slots and the nut having opposed arms extending through said slots and fixed to the reciprocable carrier.

19. In a multiple spindle machine of the character described, the combination of a base, a central column and a side housing rigid on the base, a work table revoluble upon the base and about said column, a multiple spindle tool carrier vertically slidable upon said column, said side housing shaped to over-reach the tool carrier, gearing within said over-reaching housing for driving the spindles, said gearing being accessible through the top of said over-reaching housing and including change gears, whereby the speed of the spindles may be varied.

20. A multiple spindle machine of the character described, the combination of an index work carrier, a multiple spindle tool carrier reciprocable toward and from the work carrier, the spindles being circumferentially spaced, a drive gear positioned centrally within the spindles, a plurality of intermediate shafts, permanent gearing between said intermediate shafts and the drive gear, and gearing between the intermediate shafts and spindles including change gears whereby the speed of the spindles may be varied.
